UNITED STATES PATENT OFFICE.

ARTHUR ATWATER KENT, OF ARDMORE, PENNSYLVANIA.

COUPLING AND TUNING APPARATUS.

Application filed October 30, 1922. Serial No. 597,778.

To all whom it may concern:

Be it known that I, ARTHUR ATWATER KENT, a citizen of the United States, residing at Ardmore, county of Montgomery, 5 State of Pennsylvania, have invented certain new and useful Improvements in Coupling and Tuning Apparatus, of which the following is a specification.

My invention relates to apparatus for 10 coupling and tuning circuits traversed by fluctuating or alternating current, and particularly for coupling circuits traversed by currents or oscillations of audio or radio frequency such as employed in radio and 15 kindred systems.

My invention resides in apparatus of the character utilizable in accordance with the invention of W. C. MacFadden described in his application Serial No. 595,024, filed 20 October 17, 1922.

In accordance with my invention, there is combined in a practical way with a coil support a variometer structure whose windings co-act with the coil on the support.

25 It is one of the features of my invention that the various parts of the apparatus are molded of suitable insulating material, as condensite, bakelite or the like; and it is a further feature of my invention that one 30 of the stator elements of the variometer is molded integral with the aforesaid coil support.

My invention resides in further features 35 of construction and arrangement herein- after described and relating more particularly to the disposition of the mounting or bearings for the rotor structure, the disposition of connections and the mounting and disposition of a panel and operating dial 40 and handle.

My invention resides in structure of the character hereinafter described and claimed.

For an illustration of one of the various forms my invention may take, reference may 45 be had to the accompanying drawings, in which:

Fig. 1 is a vertical sectional view of apparatus embodying my invention.

Fig. 2 is a top plan view of the same.

50 Fig. 3 is a horizontal sectional view on the line 3—3 of Fig 1, some parts shown in plan.

Fig. 4 is an inverted plan view, on smaller scale, of the structure shown in Figs. 55 1, 2 and 3.

Fig. 5 is a diagrammatic view of a circuit arrangement in which my apparatus is utilizable.

Referring to the drawings, 1 is the base member or primary coil support of insulating material, preferably molded condensite, bakelite or the like. It is preferably provided at its lower end with the integral flange 2, forming a base for the entire apparatus. At the upper end of the member 60 1 is provided an inwardly extending flange 3, preferably molded integral with the member 1 and serving as a support for and as means for correlating the variometer to the support 1 and the coil carried thereby. 65

70 The variometer structure comprises the stator elements 4 and 5 and the rotor elements 6 and 7, all preferably molded of insulating material such as condensite, bakelite or the like. The stator element or support 75 4 is preferably molded integral with the base member or primary coil support 1, and as indicated, is molded integral with the flange 3 and support 1.

Secured upon the top surface of the circular flange 3 at opposite sides thereof are the horizontally extending metal bearing blocks or members 8 and 9, upon whose upper surfaces are secured the flanges 10 integral with the stator member or support 80 5. The stator member 5, the bearing blocks 8 and 9, and the base structure are secured together by the screws 11, extending upwardly through the pads or bosses 12, Fig. 4, preferably molded integral with the base 85 structure 1, through the members 8 and 9 and flanges 10, the parts being drawn firmly together by the nuts 13 threaded upon the upper ends of the screws 11.

90 The rotor structure is secured upon and rotated by a shaft comprising the aligned sections 14 and 15, mechanically coupled but insulated from each other by the insulating coupling 16. The rotor members or supports 6 and 7 are secured to each other 100 and clamped to the shaft by the bolts 17 extending through the flanges 18 upon the members 6 and 7, each of the members 6 and 7 being closed by an integral end wall 19. The shaft section 14 extends through a hole 105 in the bearing block 8, and is provided with the collar 20 having a conical end bearing in a conical recess communicating with the aforesaid bearing aperture in the block 8. The shaft section 15 extends through a bear 110

ing hole in the member 9, and has the conical end 21 engaging in the aperture in the spring 22 secured at 23 to the block 9 and pressing inwardly against the conical end 5 of the shaft 15.

An operator's knob or handle 24, preferably of molded insulating material, is secured by screw 25 to the shaft 14. Carried by or preferably integral with the knob 24 10 is the rotatable dial 26, preferably of insulating material, carrying suitable graduations or markings 27 co-acting with an index at or upon the boss 28, preferably molded integral with the panel 29, preferably 15 of molded insulating material, secured by screws 30 to the block 8 and having the aperture 29^a through which the shaft 14 extends beyond the coil support 1.

Embedded in, or wound upon the coil support 1 and preferably wound as indicated upon the exterior thereof, is the coil or winding P, whose upper end or terminal extends through the wall of the member 1 20 and is bound under the binding screw 31 25 which extends through the flange 3 and is tapped into the bearing block 8, thereby electrically connecting the upper end of the winding P with the block 8 and therefore with the shaft section 14. From the same 30 binding screw 31 extends the conductor 32 disposed within the base member 1 and then extending through the wall thereof at 33 35 and connecting with a binding post 34 molded in the base flange 2, such binding post serving, if suitable or desirable, for making any suitable or desirable connection, as for example, to earth as hereinafter described. Molded in the flange 2 is any other 40 suitable number of binding posts 35, 36, 37, connected to different taps to the coil or winding P and serving to bring into the antenna, primary or other circuit a suitable or desirable number of turns of the winding P.

Disposed upon the rotor supports 6 and 7 45 are the rotor windings R and R¹. One terminal of the winding R¹ is connected with the shaft section 14 by conductor 38 soldered or otherwise connected to the shaft section 50 14, as at 39. The other terminal of the rotor winding R¹ is connected at 40 with one terminal of the rotor winding R, whose other terminal is connected to the shaft section 14 by the conductor 41 connected to 55 the shaft section 15 at 42. Accordingly, the rotor windings R and R¹ are connected in series with each other and have their terminals, respectively, in the shaft sections 14 and 15, and therefore in the metal bearing blocks 8 and 9.

Disposed upon the inner spherical surfaces of the stator members 4 and 5 are the stator windings S and S¹, whose adjacent terminals are connected to each other at 43, 60 Fig. 4, inside of the base member 1 and be-

tween it and the stator member 4, the ends of the conductors of the windings S, S¹ being extended through the flange 3 for that purpose. The other end of the stator winding S is connected by conductor 44 with the binding screw 45, which extends through the flange 3, which is tapped into and connects with the bearing block 9 and therefore with one terminal of the rotor winding. 70

The other terminal of the stator winding S¹ connects by conductor 46 with the binding post 47 molded in the boss or lug 48 integral with the stator member 5. 75

In the example illustrated, therefore, the stator and rotor windings are in series with each other, constituting in effect a variometer whose one terminal is at the binding post 47, the circuit extending therefrom through the stator windings S¹, S, rotor winding R, rotor winding R¹ to the bearing block 8, and thence by conductor 32 to binding post 34, which latter, when connected to earth, in effect connects the shaft section 14 to earth, whereby the approach of the hand or person of the operator, as by touching and operating the knob 24, will not have the effect otherwise occasioned by the capacity of the person of the operator. 80

In Fig. 5 there is indicated a mode of use of the above described apparatus in accordance with the invention disclosed in the aforesaid MacFadden application Ser. No. 595,024. The antenna or other absorption structure A of a radio receiving system is connected to any suitable one of the binding posts 35, 36, 37, that post being chosen which will bring into circuit between antenna A and earth or other capacity E 95 suitable number of turns of the primary P for effecting tuning of the primary circuit 100 to the received energy when the wave length of that energy lies within a suitable range of wave lengths. The binding post 34, that is, the other terminal of the primary P, is connected to earth or capacity E and also 110 to one terminal of the rotor winding comprising the coils R and R¹, or in effect to the shaft section 14. One terminal of the secondary winding of the coupling and tuning transformer described, that is, one terminal of the rotor winding R¹, is connected to the filament or cathode f of a thermionic detector having the grid g and the plate or anode a, while the other terminal of the secondary winding, that is, one terminal of the 115 stator coil S¹, is connected to the grid through the condenser C shunted by the leak resistance r. The filament receives its current from the battery b, the current being variable by the adjustable resistance or 120 rheostat r¹. In the plate or anode circuit of the detector or thermionic device V is the relatively higher potential battery B and the telephone T or any other suitable translating instrument or a suitable connection to 125

130

amplifying apparatus of any suitable number of stages.

By rotating the knob 24 the rotor members R and R¹ as a unit rotate with respect to the stator members S and S¹ and also with respect to the primary P, effecting the variation of coupling and tuning between the primary and secondary circuits as described in said MacFadden application.

10 What I claim is:

1. Apparatus of the character described comprising coil supports, one of said supports disposed within the other, one of said supports having a spherical winding surface, and means connecting the inner support at its one end with one end of the outer support.

2. Apparatus of the character described comprising a unit of molded insulating material comprising a hollow support, a second support disposed within and spaced from said first named support and having a winding surface, the inner support integrally joined at its one end to one end of the outer support.

3. Apparatus of the character described comprising a hollow support, and a second support disposed within said hollow support and secured thereto, said second support having a winding surface, and a coil support rotatable with respect to said second support.

4. In apparatus of the character described, the combination with a hollow substantially cylindrical coil support, of a second coil support having a substantially spherical winding surface disposed within and spaced from said support, and means connecting said supports to each other at their adjacent ends.

40 5. In apparatus of the character described, the combination with a substantially cylindrical hollow coil support of molded insulating material, of a second support having a substantially spherical winding surface disposed within and molded integral with said support at their adjacent ends.

50 6. In apparatus of the character described, the combination with a hollow coil support, of a stator coil support, means connecting said supports at their adjacent ends, bearing members upon said support connecting means, and coil structure supported by said bearing members and rotatable with respect to said coil support.

55 7. In apparatus of the character described, the combination with a hollow coil support, of a stator coil support, means connecting said supports at their adjacent ends, bearing members upon said support connecting means, coil structure supported by said bearing members and rotatable with respect to said coil supports, and a coil support disposed outside of said first named support.

60 8. In apparatus of the character described,

the combination with a hollow coil support, of a stator coil support, means connecting said supports at their adjacent ends, bearing members upon said support connecting means, coil structure supported by said bearing members and rotatable with respect to said coil supports, and a coil support disposed outside of said first named support and having flange structure secured to said bearing members.

75

9. In apparatus of the character described, the combination with a hollow coil support of molded insulating material, of a stator coil support disposed within and spaced from said coil support and molded integral therewith at their adjacent ends, bearing members disposed at the adjacent ends of said coil supports, a second stator coil support disposed outside of said support and means securing said bearing members and said second stator coil support to said first named supports.

80

10. In apparatus of the character described, the combination with a hollow coil support, of a stator coil support disposed within and spaced from said support, means connecting said supports at their adjacent ends, bearing members upon said support connecting means, and coil structure supported by said bearing members and rotatable with respect to said coil supports.

90

11. In apparatus of the character described, the combination with a hollow coil support, of a stator coil support disposed within and spaced from said support, means connecting said supports at their adjacent ends, bearing members upon said support connecting means, coil structure supported by said bearing members and rotatable with respect to said coil supports, and an electrical connection extending from between said coil supports through said connecting means to one of said bearing members.

105

12. In apparatus of the character described, the combination with a hollow coil support, of a stator coil support disposed within and spaced from said support, means connecting said supports at their adjacent ends, bearing members upon said support connecting means, a shaft divided into sections insulated from each other having bearings in said bearing members, rotatable coil structure carried by said shaft sections and having terminals connected, respectively, to said sections, and electrical connections extending from the space between said coil supports through their connecting means to said bearing members.

115

13. In apparatus of the character described, the combination with a hollow coil support, of variometer structure comprising a rotor and stator, a stator member disposed within said coil support and joined thereto at their adjacent ends, bearing members disposed upon the junction between said stator

120

125

130

- member and said coil support, a rotor shaft bearing in said members and having an end projecting beyond said coil support, a panel secured to one of said bearing members and 5 having an aperture through which said end of said shaft extends, and an operating handle on said shaft.
14. In apparatus of the character described, the combination with a coil support, 10 of a variometer comprising a rotor and a pair of stator members, a flange joining said coil support and one of said stator members, and rotor bearing members disposed between the second stator member and said flange.
15. In apparatus of the character described, the combination with a coil support, 15 of a variometer comprising a rotor and a pair of stator members, a flange uniting one of said stator members with said coil support, rotor bearing members disposed upon said flange, and means securing the second stator member to said coil support.
16. In apparatus of the character described, the combination with a hollow coil 20 support, of a stator winding, a support therefor disposed within said coil support, means joining said supports at their adjacent ends, a rotor winding, a shaft therefor connected thereto, a bearing for said shaft disposed upon said means joining said supports, and a connection from said stator winding extending from within said first named coil support through said means to 25 said bearing.
17. In apparatus of the character described, the combination with a hollow coil support, of a second coil support disposed within said coil support, means joining said supports to each other, coils upon said supports, rotor coil structure, a shaft therefor, a bearing for said shaft carried by said coil support structure, and a connection from the coil upon said first named coil support to said bearing.
18. In apparatus of the character described, the combination with a hollow coil support, of a second coil support disposed within said coil support, means joining said supports to each other, coils upon said supports, rotor coil structure, a shaft therefor, a bearing for said shaft carried by said coil support structure, and an earth connection to said bearing.
19. In apparatus of the character described, the combination with a hollow coil support, of a second coil support disposed within said coil support, means joining said supports to each other, coils upon said supports, rotor coil structure, a shaft therefor, a bearing for said shaft carried by said coil support structure, a connection from the coil upon said first named coil support to said bearing, and an earth connector carried by said first named coil support and connected to said bearing.
20. In apparatus of the character described, the combination with a hollow coil support, of a second coil support disposed within said coil support, means joining said supports to each other, coils upon said supports, rotor coil structure, a shaft therefor divided into sections insulated from each other, bearings for said shaft sections carried by said coil support structure, a connection from the coil upon said first named coil support to one of said bearings, and a connection from the coil upon said second named coil support to another of said bearings. 70
21. In apparatus of the character described, the combination with a hollow coil support, of a second coil support disposed within said coil support, means joining said supports to each other, coils upon said supports rotor coil structure, a shaft therefor divided into sections insulated from each other, bearings for said shaft sections carried by said coil support structure, an earth connection to one of said bearings, and a connection from the coil upon said second named coil support to another of said bearings. 75
22. In apparatus of the character described, the combination with a hollow coil support, of a second coil support disposed within said coil support, means joining said supports to each other, coils upon said supports, rotor coil structure, a shaft therefor divided into sections insulated from each other, bearings for said shaft sections carried by said coil support structure, a connection from the coil upon said first named coil support and connected to said bearing, and a connection from the coil upon said second named coil support to another of said bearings. 80
23. In apparatus of the character described, the combination with a hollow coil support, of a second coil support disposed within said coil support, means joining said supports to each other, coils upon said supports, rotor coil structure, a shaft therefor, a bearing for said shaft carried by said coil support structure, and a connection from said coil extending from the space between said coil supports through said means to said bearing. 100
24. In apparatus of the character described, the combination with a hollow coil support, of a second coil support disposed within said coil support, means joining said supports to each other, coils upon said supports, rotor coil structure, a shaft therefor, a bearing for said shaft carried by said coil support structure, and a ground connection extending from the space between said coil supports through said means to said bearing. 110
- 125
- 130

25. In apparatus of the character described, the combination with a coil support and a coil carried thereby, of a second coil support integral with said support, a second winding disposed on said second support within said first named support, and a third coil carried by said support structure and rotatable with respect to said coils.
26. Apparatus of the character described comprising a hollow coil support, a second hollow coil support disposed within said first support spaced therefrom and secured to said first support, and a third coil support rotatable within said second support.
- 10 27. Apparatus of the character described comprising a hollow coil support, a second hollow coil support disposed within said first support, said second support secured at its one end to one end of said first named support, a third coil support disposed beyond said ends of said first and second supports, and a coil support rotatable within said second and third supports.
- 15 28. Apparatus of the character described comprising a hollow coil support, a second
- 20 29. Apparatus of the character described comprising a hollow coil support, a second support having a spherical winding surface, said second support disposed within said first support and secured thereto, a third winding support disposed beyond the ends of said first and second supports and having a spherical winding surface co-axial with said first named spherical winding surface, and a coil support having a spherical winding surface rotatable within said second and third supports.
- 25

In testimony whereof I have hereunto affixed my signature this 25th day of October, 1922.

ARTHUR ATWATER KENT.
